United States Patent

Des. 240,300
Patented June 15, 1976

240,300

WATER FILTER OR SIMILAR ARTICLE

Charles Gelman and Attila Vadnay, Ann Arbor, Mich.,
assignors to Gelman Instrument Company

Filed June 27, 1975, Ser. No. 590,904

Term of patent 14 years

Int. Cl. D23—01

U.S. Cl. D23—4

Fig. 1

Fig. 2

Fig. 3

FIG. 1 is a side elevation view of a water filter or similar article showing our new design;

FIG. 2 is a top plan view thereof; and

FIG. 3 is a bottom plan view thereof.

We claim:

The ornamental design for a water filter or similar article, substantially as shown.
